UNITED STATES PATENT OFFICE.

LEWIS C. BUTLER, OF WEST BAY CITY, MICHIGAN.

DESK ATTACHMENT FOR TELEPHONES.

SPECIFICATION forming part of Letters Patent No. 478,565, dated July 12, 1892.

Application filed February 9, 1891. Serial No. 380,807. (No model.)

To all whom it may concern:

Be it known that I, LEWIS C. BUTLER, a citizen of the United States, residing at West Bay City, in the county of Bay and State of Michigan, have invented certain new and useful Improvements in Desk Attachments for Telephones; and I do declare the following to be a full, clear, and exact description of the invention, such as will enable others skilled in the art to which it appertains to make and use the same, reference being had to the accompanying drawings, and to the letters of reference marked thereon, which form a part of this specification.

15 This invention relates to new and useful improvements in desk attachments for telephones; and it consists in a certain construction and arrangement of parts, as hereinafter fully set forth, the essential features of which 20 being pointed out particularly in the claims.

25 The object of the invention is to provide a desk for telephones that may be readily attached thereto and will afford a broad writing-surface and that may be folded together, so as to be out of the way when not in use. This object is attained by the construction illustrated in the accompanying drawings, in which—

30 Figure 1 is a perspective view of a telephone with my improved desk attached thereto. Fig. 2 is an inverted plan of the desk. Fig. 3 is a section as taken on dotted line 3 3 of Fig. 2, showing the desk folded, the dotted position showing the leaf extended. Fig. 4 is 35 a section on dotted line 4 4 of Fig. 2.

35 Referring to the letters of reference, A indicates the battery-box of a telephone, on the top of which my improved desk is adapted to be secured. Said desk is formed of the two 40 parts B and C.

B indicates the body of the desk, and C an extension-leaf that is hinged thereto, as shown at a, and is adapted to fold over onto the upper face of the part B, as shown in Fig. 3.

45 Secured to the under face of the body B of the desk are the brackets D, clearly shown in Figs. 2 and 4, which are provided with the inwardly-projecting end portions c, carrying the thumb-screws e. The flange i of the top

50 of the battery-box A extends between the projecting end portion c of the brackets D and the under face of the desk, as shown in Fig. 4, and is secured by the thumb-screws e, that bear against the under face of said flange,

whereby the desk is firmly attached to the top 55 of the box A, but may be readily removed by loosening the screws e.

E indicates a sliding bail that forms a support for the hinged leaf C. The parallel portions b of said bail pass loosely through the 6c lugs d, secured to the under face of the desk and through the brackets D, which construction permits said bail to be drawn out to support the leaf C when extended, as shown in Fig. 2, and shoved back when said leaf is 65 folded up, as shown in Fig. 3 and by dotted lines in Fig. 2.

F indicates a clamp that is actuated by the coiled spring h. Said clamp is located at the upper edge of the desk and serves to retain 70 the paper in place thereon, on which any memorandum or communication may be written. The staple or screw-eye t in said clamp affords means for raising it for the purpose of inserting the paper thereunder. 75

H indicates any suitable fabric covering, which is placed upon the upper face of the desk.

It will now be apparent that by drawing outward the bail E and extending the leaf C 80 a broad writing-surface is afforded, as well as a support for the arm when writing, and when not in use the leaf may be folded upon the part B, and the supporting-bail E shoved back, when the desk will occupy but a small 85 compass.

Having thus fully set forth my invention, what I claim as new, and desire to secure by Letters Patent, is—

1. In combination with the battery-box of 90 a telephone, the desk attachment comprising the body having the extension-leaf hinged thereto, the brackets and lugs attached to the under face of the body, the bail slidably mounted on said brackets and lugs, and 95 screws passing through said brackets.

2. In combination with the body having the hinged extension, the brackets and lugs on the under face of the body, the bail slidably mounted on said brackets and lugs, and 100 the thumb-screws in said brackets.

In testimony whereof I affix my signature in presence of two witnesses.

LEWIS C. BUTLER.
